SIGNALING SYSTEM FOR RAILROADS

Jerry Bennett, Scottsville, N. Y., assignor to General Railway Signal Company, Rochester, N. Y.

Application February 4, 1932, Serial No. 590,892

5 Claims. (Cl. 246—41)

This invention relates to railway signaling, and constitutes another species of the invention disclosed in the prior application of Walter W. Wenholz Ser. No. 500,802 filed December 8, 1930, 5 and is an improvement subordinate to the invention disclosed in said Wenholz application. It is quite common in railway signaling practice to use direct current polar relays for transmitting conditions of traffic from a particular 10 signal to the next signal in the rear. Also, it is well understood that a direct current polar-neutral relay upon a change of polarity in the current for energizing the same, will cause the neutral armature to drop momentarily, this irrespective of whether the relay is a slow acting 15 relay and irrespective of how quick the change in polarity is made. The dropping of the neutral armature is attributed to a reversal of the flux in the core structure of the relay, leaving the 20 neutral armature unattracted during such reversal. Since the polar position of a home-distant relay of one signal is controlled in accordance with the energized condition of the home-distant relay of the next signal in advance in 25 a signal system of the type above mentioned, it is apparent that pole changing of one home-distant relay will cause momentary opening of the circuit of the next home-distant relay in the rear, and so on to the end of the railroad, or 30 to a point where there is a train to break up this tumble down effect. This successive dropping of home-distant relays is commonly known among signal engineers as a kick-off. In former systems of signaling such kick-off has been prevented by the addition of a repeater relay which 35 in most cases is slow acting and which repeater relay would repeat only deenergization (not pole changing) of the home-distant relay, it having been experienced that to make the home-distant 40 relay slow acting would not prevent the kick-off occurring.

In accordance with the present invention it is proposed to construct the neutral portion of the home-distant relay to permit elimination of repeater relay, by employing as a home-distant relay in a system of the type mentioned, a polar neutral relay of the neutral-retained-armature type in which the neutral armature has an auxiliary electromagnet which is inductively connected either to the circuit for the main magnet or is inductively connected to the winding of the main magnet, this neutral-retained-armature relay being constructed so that the neutral armature will not momentarily drop during the reversal of the current in the relay circuit.

Other objects, purposes and characteristic features of the present invention will in part be pointed out hereinafter and will in part be apparent from the accompanying drawing.

The accompanying drawing shows one embodiment of the present invention as applied to a double track railway signaling system, in which the trackway is signaled for one direction of traffic only.

Referring to the drawing, the track rails 1 have been shown divided by insulating joints 2 into blocks, of which the block I and the adjacent ends of the block H and J only have been illustrated. Each of these blocks includes the usual track battery 4 and a track relay T. At 70 the entrance end of each block, normal direction of traffic being from left to right, that is west to east, is located a signal S of the multiple aspect light signal type, including a clear signal lamp G, a caution signal lamp Y and a danger signal lamp R, emitting when energized light beams of green, yellow and red, respectively. Since the apparatus for each of the various blocks is the same this apparatus will be described only for the block I, like parts being designated by like reference characters having distinctive exponents.

The signal S has associated therewith a home-distant relay HDR and an approach relay AL, the home-distant relay HDR being used to control the selection of the particular light signal unit to be illuminated, and the approach lighting relay AL being used to cut energy off of all of the three light signal units under conditions when no signal is required, this in order to save energy.

Under normal clear traffic conditions in advance of the signal S the home-distant relay HDR is energized by current of positive polarity through the following circuit:—beginning at the terminal B (+), winding of the approach lighting relay AL¹, wires 10 and 11, front contact 12 of the home-distant relay HDR¹, wire 13, front contact 14 of the track relay T, wire 15, main winding 16 of the relay HDR, wires 17, 18, 100 C, 19 and 20, front contact 21, to the other terminal B (—) of said battery. It is believed that the novel features of the system can be best explained by considering the operation thereof during the passage of a train.

Operation

Let us assume that there is a train approaching signal S in the block H moving from left to right, in the normal direction of traffic as

indicated by the arrow; the entrance of the train into the block H will cause opening of the line circuit 13° due to dropping of the front contact 14° (not shown) of the track relay T° (not shown), thereby causing dropping of the approach lighting relay AL, and closure of its back contact 27. Dropping of the contact 27 of relay AL closes the following circuit for the green lamp G of the signal S:—beginning at the terminal B (+), front contact 22 of the relay HDR, wire 23, polar contact 24 to the right, wire 25, green lamp G, wire 26, back contact 27 of relay AL, to the other terminal B (—). The completion of this circuit will of course illuminate the green lamp G, to inform the engineer of the approaching train that traffic conditions in advance are clear.

As the train accepts the signal S and passes into the block I the track relay T is deenergized, thereby effecting deenergization of the relay HDR, and extinguishment of the clear lamp G of the signal S and also illumination of the red lamp R through the following circuit:—beginning at the terminal B (+), back contact 22 of relay HDR, wire 30, red lamp R, wire 26, back contact 27 of relay AL, to the other terminal B (—). As the train in question passes from the block I into the block J, signal S¹ will cause deenergization of relay HDR¹, which will result in its red lamp R being energized and its green lamp G being deenergized, in a manner as already explained in connection with signal S. Also, as the rear end of the train passes out of the block I the home-distant relay HDR is energized by current of negative polarity through the same circuit heretofore traced with the contacts 12 and 21 assuming their retracted position, thus reversing the direction of current flow. With the relay HDR energized by current of negative polarity, as is now the case, its polar contact 24 will assume the dotted position, so that if a train were to enter the block H and effect deenergization of the approach lighting relay AL, the caution lamp Y of signal S will be illuminated through a circuit including the polar contact 24 of relay HDR and wire 28, thereby informing the engineer of the train in the block H that the second block in advance, namely the block J, is occupied by another train.

As the train in question now passes out of the block J the relay HDR¹ is energized by current of negative polarity to effect operation of its contact 24¹ to the left, thereby lighting the caution lamp Y of signal S¹, all in a manner as already explained in connection with the relay HDR. Picking up of the contacts 12 and 21 of relay HDR¹ will cause a sudden reversal of polarity in the current applied to the relay HDR, but this sudden reversal of polarity of the current in the main winding 16 of the relay HDR will not result in momentary dropping of the contacts 12° and 21° of this relay, so that the next home-distant relay in the rear (home relay HDR°, not shown) will not in any way be affected by the pole changing of the relay HDR.

It may be pointed out here that the relay HDR, includes an auxiliary magnet, comprising a core 40 having a winding 41 thereon, which winding 41 is inductively linked with the main magnetic circuit of the relay HDR through the medium of the secondary winding 42. In other words, the main core of the relay HDR contains a winding 16 and a secondary winding 42, and this latter winding is connected to the winding 41 of the auxiliary electromagnet. By this arrangement

the collapse of the flux in the main core structure of the relay causes a current to be induced in the auxiliary winding 41 of the relay, and this induced current produces a flux in the core structure 40, thereby holding the neutral contact 12°, 21° and 22 all in an attracted position during the time that such induced current flows.

It may be pointed out that this induced current is not only due to the collapse of the flux in the main core structure, but is in part due to the building up of new flux in the main core in the reverse direction, from which it is apparent that the auxiliary electromagnet 40—41 will receive a substantial amount of energy, and this energy is present for a sufficient period of time to allow the main magnetic circuit of the relay to again hold its neutral armature attracted by the new current of reverse polarity.

It is thus seen that the reversal of current from negative to positive, or vice versa, in the circuit of a home-distant relay will not result in momentary opening of the circuit for the next home-distant relay in the rear controlled by the first mentioned home-distant relay, so that the undesirable kick-off heretofore mentioned is entirely absent. It may also be pointed out that as an auxiliary feature of the present invention, pole changing of the relay, such as relay HDR, from negative to positive polarity causing movement of the contact 24 from its dotted to its solid line position, causes the yellow lamp Y to be extinguished and the green lamp G to be lighted without in the meantime momentarily energizing the red lamp R, it thus avoids, what is known in signal parlance as flashing of the red, during a change from caution to clear, and vice versa.

Having thus shown one particular embodiment of the present invention, it is desired to be understood that the invention is not limited to the particular type of system as shown in the drawing, and that additions, modifications and changes may be made to adapt the invention to the particular signal problem encountered in practicing the same, all without departing from the spirit of the present invention or its scope, except as demanded by the scope of the following claims.

What I claim as new is:—

1. In a polar direct current signaling system of the multiple aspect light signal type; the combination with a railway track having successive three aspect light signals associated therewith, of a relay having a polar armature which assumes a position depending upon the polarity of current last applied to its main winding, a neutral armature and contacts, and a winding for the neutral armature deriving magnetism from said main winding, associated with each signal controlling such signal to indicate clear, caution and danger, when such relay is energized positively, negatively and de-energized respectively; and an energizing circuit for each of said relays including pole changing contacts operated by such neutral armature of the relay associated with the next signal location in advance arranged so that the direction of current flow in such circuit is reversed when the relay in advance is changed from energized to deenergized.

2. In a polar direct current signaling system of the multiple aspect light signal type; the combination with a railway track having successive three aspect light signals associated therewith; a polar neutral-retained relay associated with each signal, each of which relays has an auxiliary electromagnet acting on the neutral arma- 150

ture thereof and connected inductively to the circuit of the main winding of such relay, and controlling such signal to indicate clear, caution and danger, when such relay is energized positively, negatively and deenergized respectively; a circuit for each of said relays including neutral-retained armature pole changing contacts operated by the relay of the next signal location in advance arranged so that the direction of current flow in such circuit is reversed when the relay in advance is deenergized, and means for deenergizing a particular relay if the block next in advance of such relay is occupied by a train.

3. In a polar direct current signaling system of the light signal type; the combination with a railway track having successive light signals associated therewith; a polar neutral-retained relay associated with each signal, each of which relays has an auxiliary electromagnet acting on the neutral armature thereof and connected inductively to the circuit of the main winding of such relay, and controlling such signal to indicate clear, caution and danger, when such relay is energized positively, negatively and deenergized respectively; and a circuit for each of said relays including neutral-retained armature pole changing contacts operated by the polar neutral-retained relay located at the next signal location in advance arranged so that the direction of current flow in such circuit is reversed when said relay in advance is deenergized.

4. In a polar direct current signaling system of the light signal type; the combination with a railway track having successive light signals associated therewith; a polar neutral-retained relay associated with each signal, each of which relays has an auxiliary electromagnet acting on

the neutral armature thereof and connected inductively to the circuit of the main winding of such relay, and controlling such signal to indicate clear, caution and danger, when such relay is energized positively, negatively and deenergized respectively; a circuit for each of said polar neutral-retained relays including neutral-retained armature pole changing contacts of such relay located at the next signal location in advance arranged so that the direction of current flow in such circuit is reversed when such relay in advance is deenergized, and means for deenergizing a particular relay if the block next in advance of such relay is occupied by a train.

5. In a polar direct current signaling system of the multiple aspect light signal type; the combination with a railway track having successive three aspect light signals associated therewith, of a relay, having a polar armature which assumes a position depending upon the polarity of current last applied to its main winding and having a neutral armature, a winding for the neutral armature deriving magnetism inductively from the circuit of said main winding, associated with each signal controlling such signal to indicate clear, caution and danger, when such relay is energized positively, negatively and de-energized respectively; and an energizing circuit for each of said relays including contacts operated by the neutral armature of the relay associated with the next signal location in advance and so connected to a source of direct current that the direction of current flow in such circuit is reversed when the neutral armature of the relay in advance is changed from an attracted to a detracted position.
